FOREIGN PATENT DOCUMENTS

DE 7816353 11/1978

Primary Examiner — Ricky Pham(74) *Attorney, Agent, or Firm* — Cozen O'Connor(57) **CLAIM**

The ornamental design for a container, as shown and described.

DESCRIPTION

FIG. 1 is a perspective view of a container showing a new design;

FIG. 2 is a left side elevation view thereof, the right side being a mirror image;

FIG. 3 is a front elevation view thereof;

FIG. 4 is a rear elevation view thereof;

FIG. 5 is a top plan view thereof;

FIG. 6 is a bottom plan view thereof;

FIG. 7 is another perspective view of the container showing the container in an alternate configuration;

FIG. 8 is another perspective view of the container showing the container in an alternate partially opened configuration; and

FIG. 9 is a close up perspective view of the container's closure mechanism in a sealed configuration; and,

FIG. 10 is another close up perspective view of the container's closure mechanism in an alternate un-sealed configuration.

The dashed lines shown in the drawings are for environmental purposes only and form no part of the claimed design.
